FIREWOOD STORAGE RACK

Joseph S. Parziale, 8922 Wilson Mills Road,
Chesterland, Ohio 44026

Filed Aug. 30, 1974, Ser. No. 502,056

Term of patent 7 years

Int. Cl. D7—08

U.S. Cl. D7—212

The single figure of the drawing is a perspective view of a firewood storage rack showing my new design.

I claim:

The ornamental design for a firewood storage rack, as shown and described.
